CAN END

Richard D. Zenger, Downers Grove, Louis H. Huber, Hinsdale, and Leon M. Patarini, Chicago, Ill., assignors to National Can Corporation, Chicago, Ill., a corporation of Delaware

Continuation-in-part of design application Ser. No. 7,893, July 20, 1967. This application July 31, 1968, Ser. No. 12,968

Term of patent 14 years

Int. Cl. D9—02

U.S. Cl. D9—254

FIG. 1 is a top plan view of a can end showing our new design;

FIG. 2 is a bottom plan view thereof;

FIG. 3 is a side elevational view thereof; and

FIG. 4 is a fragmentary cross sectional view taken on the line 4—4 of FIGURE 1.

This is a continuation-in-part of design application Ser. No. D. 7,893 filed July 20, 1967 and now abandoned.

We claim:

The ornamental design for a can end, substantially as shown and described.
